CLAIM

The ornamental design for a sweat wicking headband as shown and described.

DESCRIPTION

FIG. 1 is a left side perspective view of the sweat wicking headband;

FIG. 2 is a right side thereof;

FIG. 3 is a right side elevational view thereof;

FIG. 4 is a left side view thereof;

FIG. 5 is a front view thereof;

FIG. 6 is a rear view thereof; and,

FIG. 7 is a top plan view thereof.

The broken line outline of the partial human figure in the drawing disclosure assists in illustrating how the sweat wicking headband may appear when in a position of use, but forms no part of the claimed design.
